UNITED STATES PATENT OFFICE.

ROBERT O. HENDRICKSON, OF RACINE, WISCONSIN, ASSIGNOR TO J. I. CASE PLOW WORKS COMPANY, OF RACINE, WISCONSIN, A CORPORATION OF DELAWARE.

INTERNAL-COMBUSTION ENGINE.

1,407,694.

Specification of Letters Patent. Patented Feb. 28, 1922.

Application filed February 9, 1920. Serial No. 357,176.

To all whom it may concern:

Be it known that I, ROBERT O. HENDRICKSON, a citizen of the United States, residing at Racine, in the county of Racine and State 5 of Wisconsin, have invented certain new and useful Improvements in Internal-Combustion Engines, of which the following is a specification.

My invention relates more particularly to 10 means for automatically maintaining a fixed speed of the motor or, to be more precise for limiting the fluctuation of speed of the motor by controlling the supply of explosive mixture to the engine from or by the water circulation. As the rapidity of circulation is 15 proportional to the speed of the engine, by controlling the supply of combustible gases to the engine from the water circulation the engine speed may be maintained constant 20 within narrow limits. My present invention consists in a construction and arrangement of parts whereby the throttle valve for the explosive mixture is sensitively controlled from the circulation of water in the jacket 25 of the engine, and which at the same time permits the normal position of the throttle valve to be adjusted at the pleasure of the operator. In the accompanying drawings I have shown a preferred form of invention 30 but it is to be understood that the specific disclosure is for the purpose of exemplification only and that the scope of the invention is defined in the following claims in which I have endeavored to distinguish it 35 from the prior art so far as known to me without however relinquishing or abandoning any portion or feature thereof.

In the accompanying drawings Fig. 1 is a 40 partially diagrammatic plan view of an engine to which my invention has been applied, partly in section on a horizontal plane through the water jacket and cylinders of the engine; Fig. 2 is a front elevation on an enlarged scale of a detail, parts being shown 45 in section on the line 2—2 of Fig. 3; Fig. 3 is a horizontal section of the same detail on the line 3—3 of Fig. 2; Fig. 4 is a horizontal section on an enlarged scale of a detail and Fig. 5 is a vertical section showing the 50 throttle valve.

Each part is identified by the same reference character wherever it appears in the several views.

Looking first to Fig. 1 the engine is shown 55 as of a common form, except in the respects

hereinafter pointed out, comprising the main casting 6, cylinders 7, water jacket 8 and flywheel 9 secured as usual to the crank shaft 10. The intake 11 for the combustible mixture is connected as usual by branch 60 pipes 12, 13 to the cylinders of the engine and is provided with a butterfly valve 14 pivoted at 15, which controls the flow of mixture from the carburetor to the engine cylinders. In the respects thus far described 65 the engine may be of any usual or approved character. As heretofore stated the throttle valve 14 is controlled by the circulation in the water jacket of the engine and for this purpose the water jacket is formed 70 with a circular opening 16 at its front end which opening is closed by a flexible diaphragm 17, the edges of which are clamped in position by the annulus 18 of a conical hollow casting which is truncated and terminates in a split annulus 19. Said annulus is adapted to receive a bearing for the shaft 20 of a fan 21 driven by a pulley 22, the bearing being secured rigidly in the annulus 19 by being clamped therein by means of 80 a clamping bolt 23.

A lever 24 is pivoted at 25 to a fin or bracket 26 extending inwardly from the wall of the conical portion of the casting, and said casting is diametrically slotted at 85 27, 28 to permit the free movement of the lever 24 which extends through the slots at its opposite ends. Adjacent its fulcrum the lever is pivoted at 29 between posts 30 formed on the dished circular plate 31 which 90 is secured to the diaphragm 17 by means of a bolt 32 extended through a boss 33 on said plate, the diaphragm and a washer 34, said bolt being headed on the inside as at 35 and provided with a nut 36 on the outside to clamp the parts together. The lever 95 24 is connected by a link 37 with an arm 38 formed on the trunnion of the butterfly valve. The other end of the lever is connected to a handle 40 which may be set in 100 adjusted position by means of a pawl 41 and arc rack 42. The connection between the lever 24 and handle 40 is resilient comprising a rod 43 connected to said lever and a rod 44 connected to the handle, said rod 43 105 having thereon an adjustable collar 45 and said rod 44 connected to a collar 46 which is slidingly mounted upon rod 43. Collars 45 and 46 are connected by a coiled tension spring 47. Obviously with this construction 110

the amount of pull on the lever tending to force the diaphragm inwardly or toward the adjacent cylinder may be adjusted by the means of the handle 40 after the collars 45 and 46 have been properly adjusted upon the respective rods.

Referring more particularly to Fig. 3, it will be seen that the inlet 48 for water to the water jacket is located adjacent one edge 10 of the diaphragm and directed toward the relatively narrow passage between the diaphragm and the adjacent cylinder, and the diaphragm being normally somewhat distended inwardly forms with the cylinder a 15 converging passage through which the water from the inlet is forced. By reason of this construction and arrangement the diaphragm is peculiarly sensitive to fluctuations in the speed of flow of the water and 20 therefore quickly responds to changes in the speed of the engine and with any increase of speed shifts the throttle valve to decrease the flow of combustible gases to the engine cylinder. On the other hand when 25 for any reason the speed of the engine diminishes the pressure on the diaphragm decreases and it moves inward by reason of the spring 47 to a position to more fully open the throttle valve.

30 I claim:

1. In a device of the class described an internal combustion engine having a water jacket, there being an opening in the wall of the jacket, a diaphragm closing the opening, a connection arranged to direct the flow of water substantially along the face of the diaphragm and between the same and the engine cylinder, a valve controlling the supply of combustible mixture to the engine, 35 and connections from the diaphragm to the valve for controlling the latter.

2. In a device of the class described an internal combustion engine having a water jacket, said water jacket having an opening 45 in the front wall thereof, a flexible diaphragm closing the opening, a lever pivoted transversely in front of and adjacent the diaphragm, a pivoted connection between said lever and diaphragm, a conduit for supplying combustible mixture to the engine, a valve in said conduit, and a connection from 50 said lever to said valve.

3. In a device of the class described an internal combustion engine having a water 55 jacket, there being an opening in the front walls of the water jacket, a flexible diaphragm closing said opening, a lever pivoted to extend transversely of the engine cylinder adjacent the diaphragm, a conduit for 60 supplying combustible mixture to the engine, a valve in said conduit, a connection

from the valve to one end of said lever for operating the valve, an adjustable handle and a connection including a spring from the other end of said lever to said handle. 65

4. In a device of the class described an internal combustion engine, having a water jacket thereon there being an opening in the wall of the water jacket, a diaphragm closing said opening, a support having a flange 70 between which and the edge of the opening in the water jacket the diaphragm is secured, a valve controlling the supply of combustible mixture to the engine, a connection from the diaphragm to said valve, a fan journaled 75 in said support and means for rotating the fan.

5. In a device of the class described, a combustion engine having a water jacket thereon, there being an opening in the front 80 wall of the water jacket, a diaphragm closing said opening, a lever pivoted intermediate its ends to the diaphragm and to a fixed support, an adjustable handle, a spring connection from said adjustable handle to 85 said lever, a valve controlling the admission of combustible gas to the engine cylinders, a connection from said valve to said lever, a support having a flange between which and the water jacket of the engine said dia- 90 phragm is clamped, said support being slotted for the passage of the lever, a fan journaled on said support and means for rotating the fan.

6. In a device of the class described a combustion engine having a water jacket thereon, there being an opening in the wall of the water jacket, a diaphragm closing said opening, a valve controlling the supply of combustible mixture to the engine, connections 100 from the diaphragm to the valve for controlling the latter, a water inlet so formed and located as to direct the incoming stream of water substantially parallel to the dia- 105 phragm and between the same and the cylinder.

7. In a device of the class described a combustion engine comprising a cylinder and a water jacket surrounding the same, there being an opening in the wall of the water 110 jacket adjacent the cylinder, a diaphragm secured over said opening the diaphragm and cylinder forming a contracting passage, an inlet to the water jacket directed toward said passage, a valve controlling a supply 115 of combustible mixture to the engine and connections between said valve and dia- phragm such that when the diaphragm is forced outwardly it moves the valve toward closed position.

ROBERT O. HENDRICKSON.
